UNITED STATES PATENT OFFICE.

OTTO E. DUERR AND CLETUS A. MORTLAND, OF WILKINSBURG, PENNSYLVANIA.

DISPLAY-CABINET.

SPECIFICATION forming part of Letters Patent No. 764,280, dated July 5, 1904.

Application filed December 7, 1903. Serial No. 184,044. (No model.)

To all whom it may concern:

Be it known that we, OTTO E. DUERR and CLETUS A. MORTLAND, citizens of the United States of America, residing at Wilkinsburg, in the county of Allegheny and State of Pennsylvania, have invented certain new and useful Improvements in Display-Cabinets, of which the following is a specification, reference being had thereto in the accompanying drawings.

10 This invention relates to certain new and useful improvements in display apparatus, and relates more particularly to an apparatus whereby a plurality of pieces of goods or other articles may be displayed.

15 The object of this invention is to provide an apparatus wherein a plurality of pieces of goods of any character may be successively displayed and also to provide means whereby the removal of the goods from the apparatus 20 may be readily accomplished.

A further object of this invention is to provide an apparatus whereby the bringing of the different articles into view may be readily accomplished by manual or automatic means.

25 With the above and other objects in view the invention consists in the novel construction, combination, and arrangement of parts to be hereinafter more fully described, and specifically pointed out in the claim.

30 In describing the invention in detail reference is had to the accompanying drawings, forming a part of this application, and wherein like numerals of reference indicate like parts throughout the several views, in which—

35 Figure 1 is a front elevation of our improved display apparatus. Fig. 2 is a cross-section thereof. Fig. 3 is a side elevation of the apparatus. Fig. 4 is a detail showing a certain style of goods in the display-trays, 40 and Fig. 5 is a detail view of a modified form of display-tray.

Referring to the drawings, the reference-numeral 1 indicates the casing or frame, which may be constructed of wood or other suitable material, and suitably mounted in said frame are sheaves 2 and 3, the said sheaves 2 being mounted in a permanent manner, while the sheave 3 is slidably mounted within a bracket

4, secured within said frame. Passing around these sheaves 2 and 3 are endless carriers 5, such as belts or chains, and pivotally mounted on these carriers is a plurality of display-trays 6, which may be semicircular, as shown, or of a flat construction, as illustrated in Fig. 5. The sheaves 2 being mounted in the framework, it will be readily seen that by revolving said sheaves the trays carried by the endless carriers 5 will be moved, whereby the same may be brought into the view. The movement of the said sheaves 2 is accomplished through the medium of the sheave 7, which is mounted on an extension of the shaft 8, upon which said sheaves 2 are secured, and the said sheave 7 may be revolved either through the medium of the endless belt 9, as shown in the drawings, or by a suitable driving means, such as a motor or the like. (Not shown.)

In order that the goods contained in the tray may be readily observed, the casing 1 is provided on all sides with transparent panels, the side panels 10 and rear panels 11 of which are stationary, the portion 12 of the front panel also being stationary, and to provide for the removal of goods from the cabinet the portion 14 of the front panel is slidably mounted within the casing, and secured to said portion 14 on either side thereof are cords 15, which at their upper ends are secured to drums 16, the said drums being suitably mounted within the cabinet, and a spring 17 is suitably secured between the said drums and cabinet, whereby a force is normally applied to said drums to counterbalance the weight of the portion 14 of the front panel, thus permitting the same to be readily actuated. A handle 18 is provided on the part 14 for raising the same.

In Fig. 4 the trays are shown as semicircular, and this construction is especially advantageous in the display of bolts of ribbon or cloth; but in the display of jewelry or other articles a tray such as shown in Fig. 5 might be used, and the same may be constructed of plate-glass or the like or of any other desirable material, and it will also be

obvious that the entire cabinet might be constructed of glass, as is now done in the construction of show-windows or the like.

While we have herein shown and described our invention in detail, it will be obvious that various changes may be made in the details of construction, arrangement of parts, and in the form, arrangement, and method of moving the display-trays without departing from the general spirit of our invention.

Having fully described our invention, what we claim, and desire to secure by Letters Patent, is—

In a display-cabinet, a bracket at the base thereof, a sheave slidably mounted in said

bracket, a sheave at the top of the casing having its shaft extended beyond one of the casing sides, a sheave on said projecting end of said shaft, an endless belt over said last-named sheave, and an endless carrier over said first-named sheaves, said casing having a portion thereof slidably mounted to permit access to said bracket.

In testimony whereof we affix our signatures in the presence of two witnesses.

OTTO E. DUERR.

CLETUS A. MORTLAND.
